ACUPUNCTURE NEEDLE

Everett A. Crocker, 15 White Gate Road,
North Billerica, Mass. 01821

Filed July 24, 1974, Ser. No. 491,568

Term of patent 14 years

Int. Cl. D24—02

U.S. Cl. D83—12 R

FIG. 1 is a side elevation of an acupuncture needle showing my new design;

FIG. 2 is an enlarged side elevation thereof with portions broken away to indicate indeterminate length;

FIG. 3 is a top plan view thereof;

FIG. 4 is a bottom plan view thereof; and

FIG. 5 is a side elevation of a modified embodiment of the acupuncture needle.

I claim:

The ornamental design for an acupuncture needle, as shown and described.
